US00D904328S

(12) **United States Design Patent** (10) Patent No.: **US D904,328 S**
Margis et al. (45) Date of Patent: ** Dec. 8, 2020

(54) **DISPLAY**

(71) Applicant: **Panasonic Avionics Corporation**, Lake Forest, CA (US)

(72) Inventors: **Paul Anthony Margis**, Irvine, CA (US); **Mehdi Izadyar**, Trabuco Canyon, CA (US); **Marshal H. Perlman**, Portola Hills, CA (US); **Kaname Tomita**, Osaka (JP); **Yasuhiro Araki**, Osaka (JP); **Taku Yamada**, Irvine, CA (US); **Omar Lopez**, Corona, CA (US); **Craig Allan Depner**, Trabuco Canyon, CA (US); **Sheng Tong**, Costa Mesa, CA (US)

(73) Assignee: **PANASONIC AVIONICS CORPORATION**, Lake Forest, CA (US)

(**) Term: **15 Years**

(21) Appl. No.: **29/667,014**

(22) Filed: **Oct. 17, 2018**

CLAIM

The ornamental design for a display, as shown and described.

DESCRIPTION

FIG. 1 is a perspective view of a display showing an embodiment of our new design; and, FIG. 2 is a perspective view of a display showing an alternative embodiment of our new design.

The broken lines showing the displayed image in FIGS. 1 and 2 depict environmental subject matter only and form no part of the claim; while all other broken lines depict portions of the display that form no part of the claimed design.

1 Claim, 2 Drawing Sheets
